UNITED STATES PATENT OFFICE

RALPH SALISBURY, OF LANCASTER, CALIFORNIA

AIR COMPRESSOR

Application filed November 20, 1930. Serial No. 496,916.

This invention relates to compressors, and has for an object the provision of an unusually efficient compressor which is of relatively light and simple construction.

6 A more detailed object is to provide a compressor having preferably a pair of opposed cylinders disposed diametrically with respect to a circular frame and mounted thereon for rotation about the axis thereof, each of the 10 cylinders having a piston reciprocable therein and carried by a shaft which is journaled upon the frame eccentrically with respect thereto, so that the pistons reciprocate within their respective cylinders when the shaft and 15 cylinders rotate together.

Another object is to provide guiding means whereby the cylinders are carried in rotary motion with respect to the frame when torque is applied to the shaft.

20 Another object is to provide novel means for withdrawing the compressed fluid from the cylinders, this means being in the form of flexible tubes leading from the outlet valves of the cylinders to a bore which is provided in the shaft, and a discharge tube leading from the bore, whereby the fluid compressed by the device of the present invention may be conducted therefrom.

The invention possesses other objects and 30 advantageous features, some of which, with those enumerated, will be set forth in the following description of the invention's particular embodiment which is illustrated in the drawing accompanying and forming a part of the specification.

Referring to the drawing:

Fig. 1 is a view in side elevation of a compressor embodying the principles of the present invention.

40 Fig. 2 is a vertical sectional view taken upon the line 2—2 of Fig. 1, with the direction of view as indicated.

Fig. 3 is a vertical sectional view taken in a plane perpendicular to that of Fig. 2 45 upon the line 3—3 of that figure, with the direction of view as indicated.

Fig. 4 is a horizontal sectional view taken upon the line 4—4 of Fig. 1, with the direction of view as indicated.

50 In its preferred embodiment, the compres-

sor of the present invention comprises a frame 6, having a circular track 7 supported preferably in a vertical plane upon a suitable base 8. Rigidity is imparted to the track 7 by a plurality of arms 9 which radiate from a common center, which, however, instead of being at the axis of the track 7 is disposed eccentrically with respect thereto, preferably a material distance thereabove.

A cylinder housing 11 is mounted upon the frame 6 in such position that it extends diametrically with respect to the track 7 upon which the housing 11 is guided by means of a roller 12 journaled at each end of the housing 11, and engaging the inner face of the track 7. Spaced peripheral flanges 13 on each of the rollers 12 engage the sides of the track 7, so as to prevent lateral displacement of the housing 11. The means for mounting each of the rollers 12 comprises a pair of spaced lugs 14 extending from the associated end of the housing 11, and having a pin 16 extending therebetween, the roller 12 being journaled upon the pin 16 between the lugs 14, as clearly shown upon Fig. 2.

A shaft 17 is journaled upon the frame 6, with the axis of the shaft 17 passing through the point from which the arms 9 on each side of the frame 6 radiate, with the result that the shaft 17 is disposed eccentrically with respect to the circle described by the track 7. Journals 18 and 19 are supported upon the arms 9 at the two sides of the frame 6, so as to provide suitable support for the shaft 17. That portion 21 of the shaft 17 which extends between the two journals 18 and 19 is non-circular in cross sectional configuration, preferably square, and carries a pair of guides 22 rigid therewith, each of these guides 22 extending from both sides of the shaft 17 in opposite directions. Moreover, the square portion 21 of the shaft 17 extends through opposed slots 23 in the cylinder housing 11, these slots being disposed in parallelism with the axes of opposed cylinders 26 and 27 which are formed within the housing 11. Each of the guides 22 is slidably disposed within a guideway 28 in the associated side of the cylinder housing 11, whereby rotary motion of the housing 11 with

the shaft 17 is effected, but reciprocatory motion of the housing 11 with respect to the circle described by the track 7 upon which the housing 11 is guided.

5 Pistons 31 and 32 are rigidly connected to the shaft 21 by means of piston rods 33 and 34, respectively, and are slidably disposed within the cylinders 26 and 27 respectively. Hence, as rotation of the housing 11 10 occurs and one of the cylinders, say the cylinder 26, moves from its uppermost position towards its lowermost position, the cylinder 26 will move radially away from the shaft 17, causing a partial vacuum to be developed 15 between the piston 31 and the outer end of the cylinder.

Each of the cylinders is provided with an inlet port 36 and an outlet port 37, each of which is provided with a suitable check valve 20 38. Hence, when this partial vacuum is developed, air will be drawn into the cylinder through the inlet port 36, and as soon as the cylinder has reached its lowermost extreme 25 of motion and starts its upward motion, the check valve 38 associated with the inlet port 36 will close, with the result that as upward motion of the cylinder occurs the only exit for the air which is becoming compressed is through the outlet port 37. The check valve 30 38 of each outlet port 37 communicates by means of a flexible tube 39 with a bore 41 which is provided in one end of the shaft 17. This end of the shaft 17 is revolvably received within a stuffing box 42 carried by an 35 extension 43 which extends rigidly from the journal 18, and from the stuffing box 42 any suitable discharge tube 44 leads.

Inasmuch as the cylinder housing 11 is connected to the shaft 17 by means of the radially 40 extending guides 22, rotation of the shaft will cause similar rotation of the cylinder housing 11. Accordingly, any suitable means for rotating the shaft 17 are employed, such as a sprocket wheel 46 secured to the end of 45 the shaft 17 opposite that which is engaged within the stuffing box 42.

I prefer to construct each of the guides 22 in such a manner that it is roughly channel shaped in cross sectional configuration, as 50 best shown upon Fig. 4, having a flange 51 extending from each side of the guide 22, and slidably engaging the outer face of the cylinder housing 11. A plurality of ribs or beads 52 are provided within the channel 55 defined by each guide 22, which serve not only to strengthen the entire construction, but also aid in the dissemination of heat generated during employment of the device for compressing gases.

60 It is to be understood that the details of the invention as herein disclosed, are subject to alteration within the spirit or scope of the appended claims.

65 I claim:

1. A compressor comprising a frame, a cir-

cular track thereon, a cylinder housing mounted on said track for rotation about the axis thereof, said housing having a cylinder disposed radially with respect to said circular track, a shaft perpendicular to the axis of said cylinder and journaled on said frame eccentrically with respect to said track, a piston rigid with said shaft and slidably disposed within said cylinder, and means on said shaft slidably engaging said cylinder housing to rotate the housing with the shaft. 75

2. A compressor comprising a frame, a circular track thereon, a cylinder housing disposed radially of said track and mounted thereon for rotation about the axis thereof, opposed cylinders carried by said housing, a shaft perpendicular to the axes of said cylinders and journaled on said frame eccentrically with respect to said track, a piston slidably disposed within each of said cylinders, each of said pistons being rigidly connected to said shaft, and means on said shaft slidably engaging said cylinder housing to rotate the housing with the shaft. 80

95 3. A compressor comprising a frame, a circular track thereon, a cylinder housing disposed radially of said track, rollers journaled on said housing and engaging said track to guide the housing in rotation about the axis of said track, opposed cylinders carried by 100 said housing, a shaft perpendicular to the axes of said cylinders and journaled on said frame eccentrically with respect to said track, a piston slidably disposed within each of said cylinders, each of said pistons being rigidly connected to said shaft, and means on said shaft slidably engaging said cylinder housing to rotate the housing with the shaft. 105

110 4. A compressor comprising a frame, a circular track thereon, a cylinder housing disposed within the circle described by said track, means on said housing engaging said track and guiding said housing in rotation about the axis of the track, a plurality of cylinders carried by said housing and arranged radially with respect to said circle, a shaft journaled eccentrically of said circle and disposed perpendicularly to the axes of said cylinders, a piston slidably disposed in each of said cylinders and rigidly connected to said shaft, and a guide slidably engaging each of said cylinders in parallelism with the axis thereof, each of said guides being rigid with said shaft. 115

120 5. A compressor comprising a frame, a circular track thereon, a cylinder housing disposed within the circle described by said track, means on said housing engaging said track and guiding said housing in rotation about the axis of the track, a plurality of cylinders carried by said housing and arranged radially with respect to said circle, a shaft journaled eccentrically of said circle and disposed perpendicularly to the axes of said cylinders and rigidly connected to said 125 130

shaft, and a guide rigid with said shaft and
slidable within a guideway in said housing,
extending diametrically with respect to said
circle.

5 In testimony whereof I have signed my
name to this specification.

RALPH SALISBURY.
